UNITED STATES PATENT OFFICE

KNUT MADSEN STRÅND, OF DRAMMEN, NORWAY

ELECTRICAL SWITCH

Application filed November 17, 1926, Serial No. 148,919, and in Norway November 23, 1925.

This invention relates to that type of electrical switches in which the contact-blade is so connected with its operating means that, in breaking the circuit, the blade is first moved along the contact springs and then describes an angular movement, whereas the closing of the circuit is effected by a rectilinear movement following an angular movement of the blade.

The novelty of the invention consists in providing control mechanism for the movable blade carrier that moves the latter longitudinally thereof, and prevents longitudinal movement during the angular movement of the blade and vice versa.

Various constructional forms of said mechanism are possible, but in order that the invention may be understood two of these are illustrated, by way of example, on the accompanying drawing to which reference will now be made and whereon:

Fig. 1 is a side elevation of a switch in accordance with the invention.

Fig. 2 is a part plan corresponding to Fig. 1.

Fig. 3 is a side elevation, partly in section, showing the mechanism for effecting the combined longitudinal and angular movements of the blade carrier.

Fig. 4 is a plan corresponding to Fig. 3, and

Fig. 5 shows, in side elevation and part section, a second or modified form of the operating mechanism.

Figs. 6 and 7 show further modifications.

On the drawing, 1 denotes the frame on which the switch is mounted, 2, 3 and 4 the insulating pillars supporting the various switch members, 5 the contact-springs supported by the pillar 2, 6 the contact-blade, 7 the arms constituting a carrier for the blade, and 8 a housing for the operating mechanism, supported by the pillars 3 and 4. To facilitate the insertion of the blade between the contact springs, these diverge in the direction of the housing (Fig. 2).

Within the housing 8 (Figs. 3 and 4) is an operating shaft 21. This carries a crank device 24 having a crank pin 23, to which is attached a head 22 adapted to be turned in a

horizontal plane. Said head is pivotally connected to a rod 13, so that the rod can swing in a vertical plane. By means of a second head 12, the rod is connected to a crank arm 11 keyed on a shaft 25 which is rigidly attached to the blade carrier 7. The shaft 25 is journalled in a slide 10 arranged to work in guides 14 in a support 9. Said slide has a stop 15 with an oblique forward end adapted to co-act, with a latch 18, on an arm 16 pivoted on a bracket 17 and controlled by a spring 19.

With the parts in the position shown, the switch is closed. If now, the operating shaft 21 be turned clockwise (Fig. 4) the crank pin 23, head 22 etc. move as indicated by the dotted lines, thereby causing the slide 10 and therefore the carrier 7 for the contact-blade to move horizontally to the right until the stop 15 trips past the latch 18 and projections 11^a on the crank pin bear against the pin 20 on the locking arm 16. No further horizontal movement of the slide can then take place, but during the continued turning movement of the operating shaft the crank 11 and shaft 25 are turned, so that the carrier 7 and contact-blade receive the necessary angular movement.

The angle of the crank 11 is such that under the pull of the rod 13 it necessarily moves the slide until the projection 11^a comes against the pin 20.

On the shaft 21 being turned back, the crank 11 and shaft 25 are also turned to impart an angular movement to the carrier 7 and blade 6 in the reverse direction, but the latch 18 prevents any horizontal movement of the slide 10 until the projections 11^a have lifted the latch out of engagement with the stop 15, whereupon a horizontal movement of the slide etc. ensues back to the original position, that is to say, the contact-blade is first swung into the horizontal position and then thrust lengthwise between the contact springs.

According to Fig. 5, the crank arm 11 is connected to a wiper 26. Said wiper is provided with a curved portion 28 and a straight portion 29 with which a roller 27 on the arm 16 makes contact. On the rod 13 being moved towards the right to open the switch, the por-

tion 29 is in contact with the roller 27 and prevents any angular movement of the crank pin 11 and therefore of the carrier 7 for the contact-blade 6. During a continuation of the movement of the rod 13, the curved surface 28 comes into contact with the roller and at the same time the slide 10 is brought to bear against a stop 30 on the support 9. Further horizontal movement of the slide, 10 and therefore of the contact-blade, is thus prevented, and a positive rotational movement is imparted to the crank pin 11 and consequently to the carrier 7 for the contact-blade 6, the surface 28 moving over the roller 15 27 until, as indicated by the broken lines, the surface 29 of the wiper 26 bears against a vertical surface of the support 9.

During the return movement of the rod 13 to close the switch, a positively guided swinging movement is first imparted to the crank pin 11, followed by a horizontal movement of same, so that the blade 6 is first turned into a horizontal position and is then thrust in the horizontal direction between the contact springs 5.

According to Fig. 6 the stopping and controlling device is constructed in such a way that the horizontal motion is limited by a surface 28A contacting with the roller 27 placed upon a support 34 carried by a portion 9 similar to that shown in Fig. 5. 31 denotes an arm carrying a stopping screw 32 coacting with a stop 33 and adapted for adjusting the angular motion of the device. 35 Fig. 7 shows a construction substantially similar to that shown in Fig. 6 the only difference consisting therein that a groove is arranged in the stopping and controlling device embracing the roller 27 so that any free motion of the device is prevented. The groove is provided with rounded connecting surfaces 29^b and 29^c between the straight portion and the curved portion of the guide.

It will be understood that an electrical switch according to this invention makes necessary grinding of the contacts against each other possible by means of the usual operating handle or mechanical appliances without interrupting the working. For such purpose the breaking handle may be provided with a rigid arch upon which the handle is moved during the angular motion between the outermost positions. Such arch may be provided with stops by means of which the handle is secured in its positions for opening and breaking the circuit.

Further an adjustable stop is provided by means of which the operating handle may be moved forward and backward in such a way that the contact blade receives a longitudinal motion limited so that a breaking of the circuit is avoided.

It will now be evident that also other modifications are possible without departing from the scope of the invention. For example,

bevel pinions, rotatable arms connected by rods, eccentrics, spur wheels, etc., may be used as different auxiliary means for effecting the combined angular and longitudinal movements of the contact-blade.

70

I claim:—

1. In an electrical switch the combination of stationary contacts, a co-acting movable contact-blade, a carrier for the blade, a shaft on which the carrier is secured, a slide in which the shaft is journalled, said slide being movable together with the carrier in the direction of the length of said carrier, a crank on the shaft, operating means connected with the crank, a stationary stop, and means movable with the slide under the action of the operating means to engage the stop whereafter the operating means acts to turn the shaft in the slide.

75

2. In an electrical switch the combination of stationary contacts, a co-acting movable contact-blade, a carrier for the blade, a shaft on which the carrier is secured, a slide in which the shaft is journalled, a crank on the shaft, operating means connected with the crank, a stationary stop, means movable with the slide under the action of the operating means that opens the switch to engage the stop whereupon the sliding movement ceases and the shaft is turned, and means for freeing the slide after a predetermined turning movement of the shaft in the opposite direction under the action of the operating means that closes the switch.

80

3. In an electrical switch the combination of stationary contacts, a co-acting movable contact-blade, a carrier for the blade, a shaft on which the carrier is secured, a slide in which the shaft is journalled, a crank on the shaft, operating means connected with the crank, a latch projecting into the path of the slide, a stop on the slide to engage the latch under the action of the operating means that opens the switch whereupon the sliding movement ceases and the shaft is turned, and means on the crank to lift the latch and free the slide after a predetermined angular movement of the shaft in the opposite direction under the action of the operating means that closes the switch.

95

4. In an electrical switch the combination of stationary contacts, a co-acting movable contact-blade, a carrier for the blade, a shaft on which the carrier is secured, a slide in which the shaft is journalled, a crank on the shaft, an operating disc, a crank pin on the disc, a head turnable on the pin, a connecting rod pivotally connected at one end to the head and at its other end to the aforesaid crank, a stationary stop, and means movable with the slide to engage said stop during movement of the operating disc to open the switch.

105

5. In an electric switch the combination of stationary contacts, a co-acting movable con-

110

115

120

tact-blade, a carrier for the blade, a shaft on which the carrier is secured, a slide in which the shaft is journalled, a crank on the shaft, an operating disc, a crank pin on the disc, a head turnable on the pin, a connecting rod pivotally connected at one end to the head and at its other end to the aforesaid crank, a stationary stop, means movable with the slide to engage said stop during movement of the operating disc in a direction to open the switch and means on the aforesaid crank to free the slide again during movement of the operating disc in a direction to close the switch.

15 6. In an electrical switch the combination of a frame, insulating pillars on the frame, resilient contact jaws on one of the pillars, a co-acting contact-blade, a movable carrier for the blade, a housing supported by the remaining pillars, a slide within the housing, a shaft journalled in the slide on which shaft the carrier is secured, a crank on the shaft, operating means connected with the crank, a stationary stop, means movable with the slide under the action of the operating means that opens the switch to engage the stop whereupon the sliding movement ceases and the shaft is turned, and means for freeing the slide after a predetermined turning movement of the shaft in the opposite direction under the action of the operating means that closes the switch.

7. In an electrical switch the combination of a frame, insulating pillars on the frame, resilient contact jaws on one of the pillars, a co-acting contact-blade, a movable carrier for the blade, a housing supported by the remaining pillars, a slide within the housing, a shaft on which the carrier is secured journalled in the slide, a crank on the shaft, operating means connected with the crank, a spring-pressed latch projecting into the path of the slide, a stop on the slide to engage the latch under the action of the operating means that opens the switch whereupon the sliding movement ceases and the shaft is turned, and means on the crank to lift the latch and free the slide after a predetermined angular movement of the shaft in the opposite direction under the action of the operating means that closes the switch.

8. In an electrical switch the combination of a frame, insulating pillars on the frame, resilient contact-jaws on one of the pillars, a co-acting contact-blade, a movable carrier for the blade, a housing supported by the remaining pillars, a slide within the housing, a shaft journalled in the slide on which shaft the carrier is secured, a crank on the shaft, an operating disc, a crank pin on the disc, a head turnable on the pin, a rod pivotally connected at one end to the head and at its other end to the aforesaid crank, a stationary stop, and means movable with the slide to engage the

stop during movement of the operating disc to open the switch.

9. In an electrical switch the combination of a frame, insulating pillars on the frame, resilient contact jaws on one of the pillars, a coacting contact-blade, a movable carrier for the blade, a housing supported by the remaining pillars, a slide within the housing, a shaft journalled in the slide on which shaft the carrier is secured, a crank on the shaft, an operating disc, a crank pin on the disc, a head turnable on the pin, a rod pivotally connected at one end to the head and at its other end to the aforesaid crank, a stationary stop, means movable with the slide to engage the stop when the operating disc is turned to open the switch, and means on the aforesaid crank to free the slide again after a predetermined movement of the operating disc in a direction to close the switch.

10. In an electrical switch the combination of a frame, insulating pillars on the frame, resilient contact jaws on one of the pillars, a coacting contact blade, a movable carrier for the blade, a housing supported by the remaining pillars, a slide within the housing, a shaft journalled in the slide on which shaft the carrier is secured, a crank on the shaft, an operating disc, a crank pin on the disc, a head turnable on the pin, a rod pivotally connected at one end to the head and at its other end to the aforesaid crank, means movable with the slide for controlling the position of the crank during the motion of the slide and preventing any uncontrolled motion of the same.

In testimony whereof I affix my signature.
KNUT MADSEN STRAND.
